DESIGN FOR A WHEEL FOR A ROLLER SKATE OR THE LIKE

Edward A. Grange, Alexander F. Kaptuller, and Erwin J. Schmidt, Chicago, Ill., assignors to Allied Engineering Company, Chicago, Ill., a corporation of Illinois

Application May 26, 1937, Serial No. 69,564

Term of patent 14 years

To all whom it may concern:

Be it known that we, Edward A. Grange, Alexander F. Kaptuller, and Erwin J. Schmidt, citizens of the United States, Germany, and the United States, respectively, residing at Chicago, in the county of Cook and State of Illinois, have invented a new, original, and ornamental Design for a Wheel for a Roller Skate or the like, of which the following is a specification, reference being had to the accompanying drawing, forming part thereof.

In the drawing,

Fig. 1 is a perspective view of a wheel for a roller skate or the like embodying our new design; Figs. 2 and 3 are elevational views looking at opposite sides of the wheel; and

Fig. 4 is an edge elevational view of the wheel.

We claim:—

The ornamental design for a wheel for a roller skate or the like substantially as shown.
